[57] ABSTRACT

The present inventive transformer is comprised of a first and second channel with the first channel transforming an input signal by a desired function and providing as an output the transformed input signal. A second channel transforms the input signal by an identical function and provides an output signal which is identical to the output signal from the first channel except that all frequency components of the signal in the second channel are phase shifted by 90° with respect to the signal in the first channel.

1
HILBERT TRANSFORMER

BACKGROUND OF THE INVENTION

In the field of communications systems, designs that incorporate filters which process information through two channels in a particular fashion are frequently called for. The information in only one channel is shaped by some specified transfer function, frequently a narrow-band filter. In addition, each frequency component of the signal in the first channel is phase shifted by 90° with respect to the signal in the second channel. This particular type of signal processing is called Hilbert transformation and, in the past, various approximations have been developed for achieving the desired signal relationship. In one type of prior art system, the signal information is applied through a bandpass filter to a 90° phase shifter in a first channel to obtain a Hilbert transformer approximation of the bandpass filtered signal at the output of the bandpass filter which is applied to a second channel. In a second type of prior art system, signal information is applied through a digital bandpass filter to a convolution filter which convolves the signal with a ramp voltage to develop a Hilbert transformer approximation of the filtered output signal from the digital bandpass filter which is applied to a second channel. The present invention is directed to a circuit for achieving an exact solution to this problem.

SUMMARY OF THE INVENTION

The present invention is directed to the field of signal transformers and, more particularly, to a Hilbert transformer. In one preferred embodiment of the invention, there are provided two channels with each channel having a pair of first multiplier means for receiving an input signal. Each of the first multiplier means receives a periodic function signal whose frequency defines the center frequency of the bandpass characteristics of the overall filtering function cosine signal, which signal has a frequency to which is translated the bandpass of a linear filter (see below). The outputs of the first multiplier means are fed to the inputs of four identical linear filters, respectively. The outputs of these filters are respectively fed to four second multiplier means, which multiplier means also selectively receive the sine and cosine signals for multiplication with the filter output signals. The outputs of the first channel second multiplier means are summed together to provide a transformed signal with the outputs of the second pair of second multiplier means differenced together to provide a second output signal which is transformed in an identical manner as the first signal but shifted in phase by 90°.

It is, therefore, an object of the present invention to provide an improved signal transformer.

It is another object of the present invention to provide a signal transformer wherein the signals are transformed in an identical manner but shifted in phase exactly 90°.

These and other objects of the present invention will become more apparent when taken in conjunction with the following description and drawings wherein like characters indicate like parts and which drawings form a part of this invention.

2

BRIEF DESCRIPTION OF THE DRAWINGS

FIG. 1 illustrates in block diagram form the transfer function of a Hilbert transformer;

5 FIG. 2 illustrates in schematic and block diagram form the basic circuit used in part to achieve the functions illustrated in FIG. 1;

10 FIG. 3 illustrates one preferred embodiment of the invention in schematic and block diagram form for achieving the total functions illustrated in FIG. 1;

15 FIG. 4 illustrates in electronic schematic form a circuit which may be used in one of the blocks of FIGS. 2 and 3; and

20 FIG. 5 illustrates in block form a digital circuit which may be used as one of the blocks contained in FIGS. 2 and 3.

DESCRIPTION OF THE PREFERRED EMBODIMENTS

25 In FIG. 1 there is shown an idealized Hilbert transformer 10. The transformer is comprised of two channels, one 11 and the other 12. Each channel is comprised of an identical transfer function in this example G(s), which transfer function operates upon an input signal $x(t)$ to yield substantially identical output signals $y_1(t)$ and $y_2(t)$, which signals have each frequency component shifted 90° with respect to each other.

30 In FIG. 2, one channel of implementation of the present transformer is shown. The input signal $x(t)$ is fed to multipliers 15 and 16. These multipliers also receive signals A and C, which signals will be defined below. The outputs of the multipliers are designated x_1 and x_4 , respectively. These outputs are fed to linear filters 17 and 18 which, for example, may be lowpass filters. The 35 outputs of filters 17 and 18 are designated x_2 and x_5 , respectively, and are fed to multipliers 19 and 20, respectively. Multiplier 19 also receives a signal B for multiplication with the signal x_2 . Multiplier 20 receives a signal D for multiplication with signal x_5 . The output of multiplier 19 is designated x_3 , with the output of multiplier 20 being designated x_6 . Both of these outputs are provided to combining means 21 to provide an output signal x_7 , indicative of the difference between signals x_3 and x_6 . The signals A, B, C and D are defined as periodic function signals where:

$$A = \sum_{n=-\infty}^{\infty} A_n e^{j n w_s t}$$

50 and B, C, and D are similarly defined. Defining the Fourier transform of the signal x_k as:

$$F[x_k(t)] = X_k(jw)$$

55 The Fourier transforms of the signals X_1 to X_7 are therefore given below:

$$X_1(jw) = \sum_{n=-\infty}^{\infty} A_n X[j(w - nw_s)]$$

$$60 X_2(jw) = H(jw) X_1(jw)$$

$$= H(jw) \sum_{n=-\infty}^{\infty} A_n X[j(w - nw_s)]$$

$$65 X_3(jw) = \sum_{m=-\infty}^{\infty} B_m X_2[j(w - mw_s)] = \sum_{m=-\infty}^{\infty} B_m H[j(w - mw_s)] \sum_{n=-\infty}^{\infty} A_n X[j(w - \{m+n\}w_s)]$$

$$= \sum_{m=-\infty}^{\infty} \sum_{n=-\infty}^{\infty} A_n B_m H[j(w - mw_s)] X[j(w - \{m+n\}w_s)]$$

$X_4(jw)$ may be obtained from $X_1(jw)$ and $X_5(jw)$ obtained from $X_2(jw)$ by replacing A_n and B_n by C_n and D_n

$$X_6(jw) = \sum_{m=-\infty}^{\infty} \sum_{n=-\infty}^{\infty} C_n D_m H[j(w - mw_s)] X[j(w - \{m+n\}w_s)]$$

$$\therefore X_7(jw) = \sum_{m=-\infty}^{\infty} \sum_{n=-\infty}^{\infty} (A_n B_m + C_n D_m) H[j(w - mw_s)] X[j(w - \{m+n\}w_s)]$$

Select all $m = -n$ only i.e., set $B_m = B_{-n}$ to eliminate modulation products of X :

$$\begin{aligned} \therefore X_7(jw) &= X(jw) \sum_{n=-\infty}^{\infty} (A_n B_{-n} + C_n D_{-n}) \\ &+ C_n D_{-n} H[j(w + nw_s)] \\ &= X(jw) \sum_{n=-\infty}^{\infty} E_n H[j(w + nw_s)] \end{aligned}$$

where $E_n = A_n B_{-n} + C_n D_{-n}$

set $E_n = \pm E_{-n}$

$A_n B_{-n} + C_n D_{-n} = \pm (A_{-n} B_n C_{-n} D_n)$

$$\begin{aligned} \frac{X_7(jw)}{X(jw)} &= H^1(jw) = E_0 H(jw) + \sum_{n=1}^{\infty} E_n \{H[j(w + nw_s)] \\ &+ H[j(w - nw_s)]\} \end{aligned}$$

Two interesting forms are immediately obvious:

1. set $A_1 = B_1 = -A_{-1} = -B_{-1} = 1/2j$

and $C_1 = D_1 = C_{-1} = D_{-1} = 1/2$

all others zero which makes

$$H_1'(jw) = 1/2 \{H[j(w + w_s)] + H[j(w - w_s)]\}$$

Therefore $A = B \sin w_s t$; $C = D = \cos w_s t$. This transformation takes a filter response and moves it up to a higher frequency, such as making a lowpass filter into a bandpass filter.

2. set $A_1 = -A_{-1} = D_{-1} = -D_1 = 1/2j$ and $B_1 = B_{-1} = C_1 = C_{-1} = 1/2$

all others zero which makes

$$H_2'(jw) = j/2 \{H[j(w + w_s)] - H[j(w - w_s)]\}$$

Therefore, $A = -D = \sin w_s t$; $B = C = \cos w_s t$

In FIG. 3, an embodiment of the Hilbert transformer is shown. The channels are identical in construction to the channel shown in FIG. 2 except for the inputs to the multipliers and the signs of the signals feeding the output combiners. In channel 11, multipliers 25 and 27 receive the reference signal $\sin \omega_s t$, while multipliers 26 and 28 receive the reference signal $\cos \omega_s t$. In channel 12, multipliers 16a and 19a receive the reference signal $\cos \omega_s t$ and multipliers 15a and 20a receive the reference signal $\sin \omega_s t$. The outputs from multipliers 27 and 28 are summed together in combiner 29 to provide the output signal $Y_1(jw)$, while the difference output from combiner 21a provides the signal $Y_2(jw)$. In mathematically comparing the signals Y_1 to Y_2 , it can be seen that the signal frequency components at the output of channel 12 are shifted 90° in phase with respect to the signal frequency components from channel 11, but, otherwise, each of the signals have undergone the same transformation.

In the FIGS. 2 and 3, the transformation blocks, labeled 17 and 18, 17a and 18a, and 17b and 18b, are generally shown and can be varied to fit specific applications. One specific application, analog in form, is shown in FIG. 4 as a simple R-C filter. In this application, the transfer function $H(j\omega)$ equals a divided by $j\omega + a$. If the same transfer function is to be digital in form, then the circuit of FIG. 5 can be used wherein

$$H(z) = 1 - A/z^{+1}$$

where $A = e^{+at}$, $T = \text{Sampling interval}$

The circuit is shown of a summing means 30 receiving as one input the input to the digital filters and the other input, the output of a multiplier 31 having a gain A . The output of the summing means 30 is the digital filters output, which output additionally is fed to a delay means 32 whose output is fed to a subtraction means 33. Subtraction means 33 subtracts from the delayed signal from delay 32 the presently received input to the digital filter. The output of subtraction means 33 is fed to the input of the multiplier 31.

What has been shown in the preceding description is a Hilbert transformer which is generalized in nature and can be used with any desired transfer function $H(j\omega)$.

While there has been shown what is considered to be the preferred embodiment of the invention, it will be manifest that many changes and modifications may be made therein without departing from the essential spirit of the invention. It is intended, therefore, in the annexed claims, to cover all such changes and modifications as fall within the true scope of the invention.

What is claimed is:

1. A Hilbert transformer system for transforming an input signal to provide first and second output signals respectively having frequency components phase shifted 90° with respect to each other, the system comprising:

a first channel comprised of first and second linear filters;

first and second multiplier means having their outputs connected to the inputs of said first and second linear filters, respectively;

third and fourth multiplier means for receiving the outputs of said first and said second linear filters respectively, said first and second multiplier means having as inputs said input signal, said first and third multiplier means having as inputs a first sinusoidal signal, and said second and fourth multiplier means having as inputs a second sinusoidal signal, said first and second sinusoidal signals having a frequency proportional to a desired frequency translation;

summing means for receiving the formed product from said third and fourth multiplier means and providing a first output signal;

a second channel comprised of third and fourth linear filters, fifth and sixth multiplier means having their outputs connected to the inputs of said third and fourth linear filters respectively, seventh and eighth multiplier means for receiving the outputs of said third and fourth linear filters respectively, said fifth and sixth multiplier means having as inputs said input signal, said fifth and eighth multiplier means having as inputs said first sinusoidal signal, and said sixth and seventh multiplier means having as inputs said second sinusoidal signal; and

subtraction means for receiving the formed product from said seventh and eighth multiplier means and providing a second output signal each frequency component of which is shifted 90° in phase from the respective frequency components of said first output signal. 5

2. A method employing first and second signals in mutual phase quadrature for automatically transforming an input signal into first and second output signals, which comprises the steps of: 10

combining the first signal with said input signal in a first multiplier;

transforming the combination of said first signal and said input signal by means of a first filter circuit into a first interim transformed signal;

combining said first interim transformed signal with said first signal in a second multiplier to develop a first interim output signal;

combining the second signal with said input signal in a third multiplier;

transforming the combination of said second signal and said input signal in a second filter circuit into a second interim transformed signal;

combining said second interim transformed signal with said second signal in a fourth multiplier to develop a second interim output signal; 25

combining said first and second interim output signals in a first combining circuit to develop said first output signal;

combining said first signal with said input signal in a fifth multiplier;

transforming the combination of said first signal and said input signal by means of a third filter circuit into the first interim transformed signal;

combining said first interim transformed signal with said second signal in a sixth multiplier to develop a third interim output signal; 35

combining said second signal with said input signal in a seventh multiplier;

transforming the combination of said second signal and said input signal by means of a fourth filter circuit into the second interim transformed signal;

combining said second interim transformed signal with said first signal in an eighth multiplier to develop a fourth interim output signal; and 45

combining said third and fourth interim output signals in a second combining circuit to develop the second output signal which has frequency components that are substantially 90° out of phase with respect to respective associated frequency components of said first output signal. 50

3. A Hilbert transformation system comprising:

first means being responsive to an input signal and a first reference signal for developing a first transformed signal;

second means being responsive to the input signal and a second reference signal for developing a second transformed signal, the first and second refer- 55

ence signals being in mutual phase quadrature with each other;

first and second multiplier means, coupled to said first means, being responsive to the first transformed signal and to the respective reception of the first and second reference signals for respectively developing first and second product signals;

third and fourth multiplier means, coupled to said second means, being responsive to the second transformed signal and to the respective reception of the second and first reference signals for respectively developing third and fourth product signals;

first combining means being responsive to the first and third product signals for providing a first output signal having first frequency components;

second combining means being responsive to the second and fourth product signals for providing a second output signal having second frequency components which are shifted in phase by 90° from the respective frequency components of the first signal. 20

4. The system of claim 3 wherein:

said first means includes fifth multiplier means responsive to the input signal and the first reference signal for developing a fifth product signal, and a first linear filter for developing the first transfer function in response to the fifth product signal; and

said second means includes sixth multiplier means responsive to the input signal and the second reference signal for developing a sixth product signal, and a second linear filter for developing the second transfer function in response to the sixth product signal. 25

5. The system of claim 4 wherein:

said first means further includes seventh multiplier means responsive to the input signal and the first reference signal for developing a seventh product signal, and a third linear filter coupled between said seventh and second multiplier means for developing and applying the first transformed signal to said second multiplier means in response to the seventh product signal, said first linear filter in said first means being coupled to said first multiplier means; and

said second means further includes eighth multiplier means responsive to the input signal and the second reference signal for developing an eighth product signal, and a fourth linear filter coupled between said eighth and fourth multiplier means for developing and applying the second transformed signal to said fourth multiplier means in response to the eighth product signal, said second linear filter in said second means being coupled to said third multiplier means.
